DECORATIVE CHAIN STRUCTURE

Abraham Blumstein, Forest Hills, N. Y.

Application March 29, 1945, Serial No. 585,476

7 Claims. (Cl. 59—80)

1

This invention generally relates to chain structures adapted for use in articles of jewelry such as bracelets, wrist watch bands and the like and more specifically to a novel structure of the character aforementioned embodying indicia for decorative purposes or the like.

This application is a continuation in part of my co-pending application S. N. 560,883 filed October 28, 1944, which has become abandoned.

The general object of the invention is to provide a construction whereby a variety of indicia such as letters forming initials or names or individuals, decorative signs or a combination thereof may be readily provided in flexible chain bracelets or the like, without unduly increasing the cost of manufacture of the product.

Another object of the invention is to provide elements forming indicia as aforesaid adapted to be incorporated in a flexible chain structure in the process of assembly of this latter, in a simple and expeditious manner. A further object is to provide a flexible chain structure comprising hollow members, indicia forming elements adapted for association with said hollow members and link units adapted to interconnect said hollow members and concurrently lock the indicia forming elements in fixed position relative to the hollow members, without necessity of directly securing the indicia to these latter.

Still another object of the invention is to provide a novel clasp for the ends of a chain of the character described.

These and other related objects will become apparent in the following description of the invention illustrated in the drawings, wherein:

Fig. 1 is a plan view of a wrist watch band embodying indicia according to the invention.

Fig. 2 is an enlarged bottom plan view of the portion of the structure of Fig. 1.

Fig. 3 is a fragmentary longitudinal section on line 3—3 of Fig. 2.

Fig. 4 is a transverse section on line 4—4 of Fig. 2.

Fig. 5 is an exploded view illustrating in perspective and in a much greater scale the various constituent elements of the structure.

Fig. 6 is a similar view illustrating the structure of the clasp.

Referring now in detail to the drawings, Fig. 1 shows, by way of example, a wrist watch band embodying indicia according to the invention, which is generally indicated at 19 and is formed of lengths of chain or band sections 11, 12 interconnected by a clasp 13, the construction whereof will be hereafter described. Each of said sec-

2

tions comprises a series of elongated open ended hollow members 14, which, in the embodiment illustrated, are shown as hollow rectangular parallelepipeds, arranged side by side and interconnected to form a flexible structure by means of composite link units to be described.

Superimposed upon the hollow members 14, are indicia forming elements 16, consisting of a substantially flat body portion 17 which is bent 10 at its opposite ends at right angles to provide portions 18 extending in juxtaposition to the ends of the hollow members and apertured as at 19, for the purpose which will become hereafter apparent (see particularly Figs. 4 and 5). The flat 15 body portion 17 may be cut to define any desired letter or sign, as exemplified by the elements shown in Fig. 5, or otherwise shaped for ornamental purposes.

Two series of elements 20 and 21, which form 20 the aforementioned link units, are arranged along the opposite ends of the hollow members 14 in offset relation thereto, and oppositely extend into pairs of contiguous members, through the 25 apertures 19 formed in the portions 18 of the indicia elements, for interlocking engagement within the members.

Each of said elements 20 comprises a head 22 and two parallel prongs 23, preferably made integral with the head and of rectangular cross-section, 30 which project from the head in parallel spaced relation to one another. In the embodiment illustrated, the ends of said prongs are cut to define therein identically disposed hook-shaped portion 24 and the prongs form a substantially 35 resilient structure due to their small cross-sectional dimension.

Each of the elements 21 likewise comprises a head 26 and a pair of spaced prongs 27 generally identical in shape and dimension to the 40 corresponding portions of the element 20, except that the ends of the prongs 27 are cut to define therein hook-shaped portions 28 oppositely disposed relative to the hook-shaped portions 24 of the prongs of elements 20 and complementary 45 thereto. Of course, the described arrangement of hook-shaped portions at the ends of the prongs 23 and 27 may be modified by forming oppositely disposed hook-shaped portions in each pair of prongs as disclosed in my aforementioned co-pending application and the conformation of the prong ends may be otherwise changed, provided complementary interlock surfaces are defined in the opposed elements 20 and 21.

As clearly shown in Fig. 3, the dimension of 55 the cavities 29 of the hollow members 14 is such

that two juxtaposed prongs of adjacent elements 20 or 21 may be received in one of said cavities and a clearance provided between the prongs and the inclosing walls of the member 14, and the distance between the parallel prongs of each element 20 or 21 is somewhat greater than the thickness of the juxtaposed walls 30 of the contiguous members 14 so that a relative displacement of the associated parts is permitted.

In order to assemble a length of chain, the indicia elements 16 are placed onto the hollow members 14 (in the position hereinbefore described and shown in Fig. 4) and the prongs 23 and 27 of the elements 20 and 21 are inserted through the apertures of the indicia elements 16 into the cavities of contiguous members 14 from the opposite ends thereof, to enclose the juxtaposed lateral walls of said members (see Figs. 2 and 5); the elements may then be moved toward one another to force their prongs into the position shown in Fig. 2 wherein the complementary surfaces of their respective hook-shaped portions 24 and 28 are interlocked. As will be apparent, a plurality of link units are formed in this manner, which interconnect successive pairs of contiguous members 14 and concurrently maintain the indicia elements 16 in fixed position relative to said members.

The inherent resiliency of the prongs obviously will permit sufficient relative displacement of the ends of the prongs 23 and 27 respectively to allow the hook-shaped portions of the former to pass over the hook-shaped portions of the latter and will then cause the prongs to spring back to their normal position, thereby securely interlocking the same.

The length of the prongs is such that, when the same are interlocked, the inner flat surfaces 31 and 32 of the heads 22 and 26 of the elements 20 and 21 will abut against the outer face of the portions 18 of the indicia elements and maintain said portions in contact with the opposed ends of the contiguous members 14 thereby preventing axial displacement of the members relative to each other, and insuring straight formation of the chain structure. The indicia elements are concurrently locked to the members 14 and function as an integral part thereof, and no direct connection of the indicia elements with the members is required. Of course, those of the members 14, if any, that do not carry an element 16, will be of somewhat greater length, to compensate for the absence of the portions 18 of the element 16 and permit the heads 22 and 26 to abut directly against the ends of the member.

Clearly, the structure described possesses a considerable degree of flexibility. Since the prongs inserted into the cavities of the members 14 do not occupy all the space within such cavities, but a substantial clearance is provided between the prongs and the surrounding walls of the members, it is apparent that the members may be caused to assume different relative angular positions with the resulting bending of the chain.

To interconnect the opposed ends of the chain sections 11, I provide a novel clasp. This clasp comprises a member 34, suitably secured, as by welding, to the end member 14 of one of the chain sections, having at one end thereof a pair of upstanding lugs 35, and provided at its other end with a slotted portion 36 terminating in the upstanding lock elements 37. A flat member 38 has an end portion 39 pivotally connectible to said

lug 35 and is slotted at its free end, as shown at 40.

The inherent resiliency of the portion 36 of the member 34 permits sufficient displacement of the elements 37 toward one another to allow of the passage thereof through the slot 40 of the member 38 and thereafter expansion of the elements into locking engagement with the edges of the slot. Since the chain members 14 are displaceable relative to one another to a certain extent, as described, it is evident that the upstanding elements 37 may be inserted between two adjacent members 14, to locate the end of one of the chain sections between the members 34 and 38 of the clasp and to lock the same therein, the height of the elements 37 being of course such as to permit the elements to project upwardly from the members 14 for interlocking engagement with the clasp member 38 in the manner described.

It will be understood that changes and modifications may be made in the structures described and illustrated in the drawings, without departing from the spirit of the invention or exceeding the scope of the claims.

I claim:

1. In a chain structure, in combination with a series of hollow members arranged side by side, a number of indicia elements each associated with one of said hollow members and having portions extending in juxtaposition to the ends of the member, and a number of link units for interconnecting said hollow members and securing the associated indicia elements thereto, each of said link units extending through a pair of contiguous hollow members and through the portions of the indicia elements juxtaposed to the ends of said contiguous hollow members.

2. A decorative chain comprising a series of open-ended hollow members arranged side by side, a number of indicia elements each embodying an indicia defining portion extending in juxtaposition to the body of one of said hollow members and apertured portions extending in juxtaposition to the ends of the member, and a number of link units for interconnecting said hollow members and securing the respective indicia elements thereto, each of said link units extending through a pair of contiguous hollow members and through the apertured portions of the indicia elements juxtaposed to the ends of said contiguous hollow members.

3. A decorative chain comprising a series of open-ended hollow members arranged side by side, indicia defining elements associated with said hollow members having apertured portions extending in juxtaposition to the ends of the hollow members, and a series of link units each comprising a pair of elements disposed adjacent the opposite ends of two contiguous hollow members in juxtaposition to the apertured portions of the respective indicia elements, said elements of the link unit embodying projections oppositely extending through the apertured portions of the indicia elements into said contiguous hollow members and interlocked therein.

4. In a chain structure comprising a series of hollow members arranged by side by side, indicia elements each carried by one of said hollow members and having apertured portions extending in juxtaposition to the opposite ends of the member, and a series of links each comprising a pair of heads juxtaposed to the apertured portions of the indicia elements carried by a pair of contiguous hollow members, said heads being interconnected by spaced elements oppositely

extending through the apertured portions aforesaid and the contiguous hollow members.

5. A chain structure comprising a series of open-ended hollow members arranged side by side, a plurality of indicia elements each associated with one of said hollow members and embodying an indicia defining portion and apertured portions extending in juxtaposition to the ends of the member, and a series of link units each comprising a pair of elements having heads juxtaposed to the apertured portions of the indicia elements associated with a pair of contiguous hollow members, said elements of the link unit embodying projections oppositely extending through the apertured portions of the indicia elements aforesaid into said contiguous hollow members and interlocked therein.

6. In a chain structure comprising a series of chain members arranged side by side and interconnected for limited lateral relative displacement, a clasp for interconnecting the ends of the chain comprising a member secured to one of the ends of the chain and embodying at its free end an upwardly extending expandible portion adapted to be inserted between two contiguous chain members of the opposite end of the chain and to project therefrom, and an element pivoted at one end thereof to said member and interlockable at its other end with said upwardly extending expandible portion of the member by contracting said expandible portion thereof. 30

7. In a chain structure comprising a series of chain members arranged side by side and interconnected for limited lateral relative displacement, a clasp for interconnecting the ends of the chain comprising a member secured to one of the ends of the chain formed at its free end with a resilient bifurcation embodying an upwardly extending terminal portion adapted to be inserted between two contiguous chain members of the opposite end of the chain and to project therefrom, and an element pivoted at one end thereof to said member and provided at its free end with a slot, the upwardly extending terminal portion of the resilient bifurcation aforesaid being insertable through said slot of the pivoted element and adapted to expand into locking engagement with the edges of the slot.
